UNITED STATES PATENT OFFICE.

LOUIS GATHMANN, OF CHICAGO, ILLINOIS.

MIDDLENS-PURIFIER.

SPECIFICATION forming part of Letters Patent No. 241,133, dated May 10, 1881.

Application filed April 5, 1881. (No model.)

To all whom it may concern:

Be it known that I, LOUIS GATHMANN, of Chicago, State of Illinois, have invented certain new and useful Improvements in Middlens-Purifiers; and I do hereby declare that the following is a full, clear, and exact description thereof, reference being had to the accompanying drawings, and to the letters of reference marked thereon, which form a part of this specification.

10 My invention relates to improvements in middlens-purifiers, having for their several objects the variation of the draft upon the several sections of the screens and the collection of the dust within the purifier and its separate discharge therefrom.

15 The improvements, which have reference to the variation of the air-currents, and which also refer to the retention of the dust, consist in bodies of cloth of different thickness or close-ness of mesh arranged over the several sections 20 of the screens, or between the screens and the suction-fan of the purifier, the spaces between the screens and the dust-arresting and draft-regulating cloth being divided into chambers 25 by means of vertical partitions, for the purpose of maintaining a separation of the several currents through the screens and their corresponding regulating cloths.

20 In the drawings, Figure 1 is a side elevation 30 of a purifier. Fig. 2 is a central longitudinal vertical section of the same. Fig. 3 is a bottom view. Figs. 4 and 5 are views of the several dust-arresting and draft-regulating cloths detached; and Fig. 6 is an enlarged view, in 35 transverse section, of the traveling fan that works beneath the screens.

A is the purifier frame and case.

B, B', and B² are three several sections of a vibrating screen, increasing in size of mesh in 40 the order given.

D, D', and D² are vibrating dust-arresting and draft-regulating screens or cloths arranged to respectively intercept the air-current from the several screens B, B', and B², and also in- 45 creasing in size of mesh, or otherwise constructed to give increased freedom of passage to the air, in the order given.

C, C', and C² are partitions substantially dividing the space between the screens B, B', and 50 B² and cloths D, D', and D² into as many chambers, so that the air passing upward through

the several sections of the screen on its way to the fan F² will also pass through the corresponding sections of regulating cloth above them, respectively. The cloths are secured to 55 open frames, two of them, D and D', being in a single frame, F, arranged above and parallel with the inclined screens. The third, D², is set in the frame F' nearly vertical, as shown. Each cloth-frame is provided with a knocker, 60 K, operated from the fan-shaft, as indicated, or otherwise. Passages o and o', above the partitions C and C', and o² at the end of the frame F, afford a slight horizontal current of air as it seeks through them the freer openings of the 65 coarser cloths. The combined action of the currents, cloths D and D', and knocker K of frame F is therefore as follows: The dust is raised by the current from the sieves, is arrested by the cloths D and D', and is momentarily de- 70 tached by the knocker. In again being drawn to the cloths by the main current it is drawn along toward the coarser cloth D² by the horizontal draft mentioned, and so ultimately reaches the said cloth D². Here the gravity 75 of the dust carries it downward at each suc-cessive knocking, and it finally falls upon the wings a a, forming chutes, whence it is dis-charged and disposed of as desired. The set-ting of the dust from the cloth D² is facilitated 80 by the said wings a a, which partly cut off or greatly reduce the force of the current through portions of said cloth.

The several bodies D, D', and D² of cloth may either be of varied size of mesh, or, say, 85 three thicknesses of a given mesh may be ap-plied to section D, two to section D', and one to section D². The object and effect are, first, to produce currents of different force through the several screen-sections B, B', and B², and, 90 second, to arrest the dust taken from the mid-dlings by such currents.

Proceeding next to the screen-cleaning de-vice, S is a shaft extending beneath the screens, from one end to the other of the machine, hav- 95 ing the toothed pinions s s at its extremities, which are fitted to and rest upon the transverse racks r. Opposite the several screen-sections the shaft is provided with rubber or other flexi-ble fans or wings w, having their free edges 100 straight and preferably smooth. At a central point of the shaft is a link, m, Figs. 2 and 3,

in which the shaft turns, and to which are attached the ends of a cord, *c*. Said cord passes over the pulleys *p* in substantially the same horizontal plane, and at a suitable point between the adjacent pulleys, as shown, has affixed thereto the button or knob *t*. Seizing this button with the hand and moving it to and fro between the adjacent pulleys *p*, the shaft *S* is obviously impelled from side to side 5 of the machine. Resting by the fixed pinions *s* upon the rack *r*, it is, of course, rotated as it advances and recedes.

If the shaft *S* is set to bring the wings *w* very near the screens, a brief sharp blast is introduced at all points of the screen successively during the passage of the fan-shaft from side to side of the machine, the violence or gentleness of which will, of course, depend upon the rapidity with which said shaft is made to travel. The effect of the blast from the cleaner-fan is to clear the meshes as effectively as if a brush were used, and the wearing effect of the brush upon the screen-cloth is wholly avoided.

25 The racks *r* should preferably be made vertically adjustable, in order that the distance between the fans *w* and the screens may be varied at pleasure.

Obviously the traveling fan may be automatically operated by suitable connection with the main fan or driving shaft.

Having thus described my invention, I claim—

1. In combination with a series of purifier screens of varying degrees of fineness, a corresponding series of cloths, varying in closeness of texture, arranged with the several screens and the fan to vary the strength of the air-currents through the several screens, substantially as described.

2. The combination, with the screens of a middlings-purifier, of the several cloth-sections of varying mesh or density, arranged to vary the force of the air-current through the several screens of the purifier, and also adapted 45 and arranged to intercept the dust from the screens, substantially as described.

3. In combination with the several varying screen-sections and the several varied cloth-sections of the purifier, a partition or partitions arranged between the screens and cloths, whereby the air-current passing through a given screen must find escape mainly through the corresponding cloth, substantially as and for the purposes set forth.

4. In combination with the fan, the sectional screen, and the sectional dust-arresting cloths, varying in openness, as described, the partition *C*, arranged to direct the air-current from a section of the screen mainly to and through 60 the corresponding section of the cloth, and also arranged to afford the passage *o*, whereby the dust detached by the knocker may be gradually drawn from one section to another of the cloth by a minor horizontal draft or current 65 near the cloth, substantially as described.

5. The chutes *a a*, formed by the cutting away of the tail-board to give passage to the air-current, in combination with the arrester *D²* and its knocker, the arrester being arranged 70 in a vertical, or nearly vertical, position above the tail-board, substantially as described.

In testimony that I claim the foregoing as my invention I affix my signature in presence of two witnesses.

LOUIS GATHMANN.
